SLEEVE COMPRESSING TOOL

William A. Vinson, Madera, Calif.

Application September 9, 1946, Serial No. 695,593

23 Claims. (Cl. 153—1)

1

My invention relates to a sleeve compressing device and more particularly to a tool for inwardly deforming a sleeve into engagement with a wire-like member positioned therein preparatory to the deformation. It is particularly adapted to the end-to-end connection of two wires by a sleeve telescoping with the end of each wire. It is in this connection that the invention will be particularly described.

Heretofore sleeve-compressing tools have been relatively massive and difficult to use. In addition, prior tools of this nature have required manual placement of a sleeve in a device preparatory to the deforming operation.

It is an object of the present invention to provide a tool in which the sleeve is retained between jaw members during the time that the wire-like member is inserted, and in which strong deforming forces can be easily applied to deform the sleeve inwardly to engage the wire-like member.

Another object of the invention is to provide a tool of this type which is adapted to operate on various sized sleeves.

A further object of the invention is to provide a tool which contains a plurality of the sleeves and which feeds these, one at a time, to an operating station preparatory to deformation thereof.

Another object of the invention is to provide a tool adapted to receive a magazine containing a plurality of sleeves held therein in side-by-side relationship. Further objects reside in the provision of a magazine of this type which is of novel construction, also the provision of a magazine which cooperates novelly with the feeding elements of the tool.

Another object is to provide a tool which can be readily adjusted for magazines containing different sized sleeves, whereby the magazine containing the appropriate sized sleeve can be inserted in the tool and later removed, with any remaining sleeves still within the magazine, when the particular job is completed.

Another object of the invention is to provide a light weight and readily portable tool for compressing or inwardly deforming a sleeve or other member at one or more positions while retained in operating position at an operating station.

Further objects and advantages of the invention will be evident to those skilled in the art from the following description of an exemplary embodiment:

Fig. 1 is a longitudinal sectional view of the tool with the internal mechanism shown in an intermediate position.

2

Figs. 2 and 3 are transverse sectional views taken along the correspondingly numbered lines of Fig. 1.

Fig. 4 is a fragmentary side view of the upper end of the tool, taken as indicated by the line 4—4 of Fig. 2, with portions broken away.

Fig. 5 is a transverse sectional view taken along the line 5—5 of Fig. 1.

Fig. 6 is a fragmentary perspective view of the upper end of one of the jaw members of Fig. 1.

Fig. 7 is a side view of a sleeve connecting two wire-like members disposed end-to-end.

Fig. 8 is a side view of the sleeve before inward deformation thereof, and

Fig. 9 is a sectional view taken along the line 9—9 of Fig. 8.

Referring particularly to Figs. 7, 8, and 9, the compression tool illustrated is particularly designed for the inward deformation of a sleeve 12 against a wire-like member 13 as by exerting a localized pressure on one side of the sleeve to deform same inwardly and produce a depressed portion 14. Such a depressed portion may be on only one side of the sleeve or may, by use of suitable jaw members, be simultaneously or sequentially formed on opposite sides of the sleeve. The inward depression or deformation will be sufficient to clamp the wire-like member 13 in the sleeve and is usually sufficient actually to deform the member to provide a positive lock against withdrawal from the sleeve. As a later operation, the tool of the invention is adapted to form another depression 14' to clamp another wire-like member 13' in the other end of the sleeve to connect the members 13 and 13' mechanically and, if desired, electrically.

The sleeve 12 may initially be a length of seamless tubing or, as suggested in Fig. 9, it may be a cylinder formed from sheet material and bent into cylindrical shape with its adjacent ends abutting or facing each other in a longitudinal zone 15. In the preferred practice of the invention the sleeve is initially deformed, before use in the tool of the present invention, at its central section to form a central depressed portion 16, preferably opposite the zone 15. Alternatively, this central depressed portion can be formed by the tool itself, as an initial operation, if the sleeve is not initially deformed. Such a central depressed portion acts as a stop means limiting the insertion of the wire-like member. Thus, if two wire-like members 13 and 13' are to be connected by the sleeve 12, as suggested in Fig. 7, the central depressed portion 16 will limit the insertion of both members and will re-

tain their adjacent ends slightly separated. At the same time, the stop action of the depressed portion 16 permits sliding of the sleeve while in the jaw means of the invention by pressure applied to the wire-like member, all as will be later described.

Referring particularly to Fig. 1, the tool of the invention includes a body 18 including a base section 19 and side sections 20 and 21 bent from the plane thereof to form a structure which is essentially channel-shaped throughout a major portion of its length. The lower section of the body 18 provides a handle-like portion 22 adapted to fit in the palm of the hand of the operator. The base section 19 provides a projection 23 limiting the upward movement of the hand and normally engaging the hand at the base of the thumb. The fingers of the hand are adapted to encompass the lower section of a handle 25 between projections 26 and 27 thereof.

The upper ends of side sections 20 and 21 provide relatively deep channels 28. Each channel slidably receives a corresponding positioning member 29 and 29' and mounted in a manner to be hereinafter described. These positioning members provide aligned notches or troughs 30 and 30' in portions of the members lying beyond the side sections 20 and 21, as best shown in Fig. 2. Either of the troughs 30, 30' is adapted to receive and position the ends of the wire-like member 13 or 13' to guide its insertion into the sleeve 12 when positioned at an operating station. This operating station is adjacent the troughs 30, 30'.

Traversing the side sections 20 and 21 and suitably secured thereto is a shaft 32 on which the handle 25 hinges. The side section 21 carries an inward-extending projection 33 acting to restrain one end of a spring 34 looped around the shaft 32 with its other end extending beneath the handle 25. This spring normally urges the handle 25 to its extended position, shown in Fig. 1, as determined by engagement with abutting stop members 36 bent inward from the side sections 20 and 21 as best shown in Figs. 1 and 2.

The body 18 is adapted to receive a magazine 38 in which is contained a plurality of the sleeves 12 disposed in side-by-side relationship. The body 18 is adapted to receive magazines containing sleeves of different size and provision is made for retaining the selected magazine in the tool and for moving the sleeves, one at a time, to the operating station 31. It is preferred that the magazine 38 be made of thin sheet metal or other relatively cheap material so that it can be discarded in favor of a new factory-filled magazine, when empty.

In the illustrated embodiment the magazine 38 includes (see Figs. 1, 2, 3 and 5) a base wall 40, two side walls 41 and 42 spaced to slide between the side sections 20 and 21, and two flanges 43 and 44 extending substantially parallel to the base wall 40. All of these walls are preferably formed by bending sheet material into the shape shown, the walls cooperating in defining a sleeve-containing chamber 45. The ends of the flanges 43 and 44 are spaced from each other to define a passage 46 facing the base section 19 and giving access to the sleeves 12 in the chamber 45.

When the magazine 38 is filled with a series of the sleeves 12, the lowermost end sleeve will be retained in the chamber 45 by a pair of tabs 47 bent inwardly from the base wall 40 at its lower end (see Figs. 1 and 3, for example). The uppermost end sleeve is releasably retained in the chamber 45 by any suitable releasable means,

shown in Figs. 1 and 2 as comprising a spring-like tongue 50 extending into the upper end of the chamber 45 and formed on each of the flanges 43 and 44. By way of example, the upper ends of these flanges may be longitudinally slit to provide the tongues 50 which are then bent inwardly of the passage to resiliently engage the end sleeve at the upper end of the series. Various other releasable means may be employed without departing from the spirit of the invention.

The body 18 provides a means for retaining the magazine 38 in fixed longitudinal position and for releasing the magazine when it is to be withdrawn in empty or partially emptied condition. This means is best shown in Fig. 1 as including a lock member 51 hinged to the bottom of the base section 19 by a pin 52 and providing a thumb tab 53 by which the member 51 can be manually moved. When in the position shown, the lower end of the magazine 38 engages the top of the member 51, thus preventing downward movement of the magazine. The member 51 also carries a clip 54 which is extensible into a horizontally-elongated slot 55 near the bottom of the base wall 40 of the magazine. This prevents forward movement of the magazine when the member 51 is in the position shown. However, the magazine can be released for withdrawal by swinging the member 51 away from the magazine, the clip 54 swinging outwardly in the passage 46 of the magazine. This releases the magazine from its previously locked position so that the magazine can be removed upwardly from the tool. Alternatively, if all of the sleeves have been emptied, the magazine may be allowed to drop downwardly from the tool. New magazines are always inserted from the top of the tool and, when in proper position, are locked in place by swinging the member 51 to extend the clip 54 into the slot 55.

Means is provided for resiliently urging the series of sleeves 12 upwardly in the chamber 45 of the magazine 38 so that when the uppermost sleeve is removed the remaining sleeves move upwardly to dispose the next sleeve in the top position. Various means, associated either with the magazine or with the body 18 or both, may be used within the spirit of the invention. The preferred arrangement is shown in Fig. 1 as including a spring-actuated reel 56 mounted in a housing 57 of the body 18 and around which is wrapped a flexible strap or cord 58 which extends through an opening 59 of the base section 19. The free end of the strap 58 is connected to a clip 60 or other means for engaging the lowermost sleeve. In the illustrated embodiment the clip 60 includes a tongue 61 bent to hook beneath the lowermost sleeve and extending into the chamber 45 through the passage 46 of the magazine. The clip 60 also carries a guide means, preferably a pair of members 62, one on each side of the tongue 61, to slide along the inner wall of the base section 19 to hold the hooked portion of the tongue 61 within the chamber 45. The tongue 61 and the member 62 are somewhat resilient and diverge from each other as suggested in Fig. 1. This divergence prevents complete withdrawal of the clip 60 into the housing 57, with consequent unwinding of the spring actuating the reel 56, the tongue 61 and the members 62 engaging the walls of the passage 59 to prevent this. With this construction it will be apparent that a completely-filled or partially-filled magazine may be moved downwardly into the body 18. As soon as the lower-

most sleeve of the series is hooked by the tongue 50, the sleeves will be moved toward the upper end of the magazine and a resilient pressure will be placed thereon, urging the uppermost sleeve against the tongues 50. As the magazine is forced further into the body 18 the spring of the reel 56 unwinds, as does also the strap 58, the clip 60 being moved downwardly in the body 18 to retain the resilient upward pressure on the sleeves 12.

The invention includes means for moving the uppermost sleeve of the series from the magazine and upwardly to the operating station and for then inwardly deforming the sleeve against the member 13 which has been inserted into the sleeve when in the operating position at the operating station. The preferred arrangement for accomplishing this involves a carriage structure, indicated generally by the numeral 65 and providing a suitable jaw means including first and second jaw members 66 and 67 for transporting and deforming the sleeve. In general, the carriage structure 65 is manually slideable in the body 18 so that it moves longitudinally of the magazine 38. In addition, the jaw members 66 and 67 are movable toward and away from each other, as by being hinged together, as will now be described.

The jaw member 66 carries two downwardly extending legs 69 which are slideable relative to the body 18 and which are disposed in the corners thereof formed by the base section 19 and the side sections 20 and 21. The lowermost ends of these legs 69 provide arms 10 extending toward the handle 25 to receive rivets or pins 11 which hinge the lower end of the jaw member 67. This jaw member 67 provides a body portion 12 and a cylindrical post 73 depending therefrom and fixed in an opening 74 (Fig. 5) of a bottom member 75 of the jaw member 67. This jaw member 67 is thus of a sectional construction and the bottom member 75 is bifurcated to provide arms 76 lying parallel to the arms 10 and receiving the rivets or pins 11 to effect the hinging of the jaw members.

The carriage structure 65 and its jaw members 66 and 67 can be moved vertically, relative to the body 18, by pressure exerted by the thumb of the hand when engaging a cocking handle 78 disposed between the body 18 and the operating handle 25. This cocking handle 78 is secured to the side of a bar 80, forming another part of the jaw member 67, so as to dispose the handle in a location convenient to the thumb.

The bar 80 is adjustably connected to the body portion 72 of the jaw member 67. In the preferred arrangement the bar 80 carries a pin 81 which can be positioned in any one of a plurality of openings 82 in the face of the body portion 72. This body portion carries a stud 83 extending through an elongated slot 84 of the bar 80 and which threadedly receives a thumb screw 85 which, when tightened and with the pin 81 in the selected opening 82, clamps the bar 80 to the body portion 72.

Surrounding the post 73 is a spring 86 with its upper end bearing against the body portion 72 and its lower end bearing against a plate 87 comprising an inwardly bent tab of the side section 21, this plate providing an opening slideably receiving the post 73. When the cocking handle 78 is forced downward against the compression of the springs 86, the entire carriage structure 65 is forced downward as a unit. When the pressure on the cocking handle 78 is relieved,

the spring 86 forces the carriage structure upwardly as a unit to a position determined by the cam means to be later described or by a suitable stop means, shown as an adjustment screw 88 threaded through the body member 75 and suitably locked in position as by the set screw shown, the end of this adjustment screw engaging the plate 87 to determine the maximum upward position of the carriage structure 65.

The positioning members 29 and 29' are connected by rivets 89 (Figs. 1 and 4) to opposite sides of the bar 80 whereby they move up and down with the bar. From the point of connection to the bar, each positioning member extends upwardly and outwardly through the corresponding channel 28 and thence parallel with the adjacent side section 20, 21 in that portion which provides the troughs 30, 30', finally bending inwardly toward the corresponding side section.

The upper ends of the jaw members 66 and 67 provide suitable notches 92 facing each other and cooperating, when the jaw members are moved toward each other, in defining at least one sleeve-receiving space. The preferred arrangement provides a plurality of pairs of such notches of progressively different size to accommodate sleeves 12 of different external diameter.

The invention includes means for moving the end sleeve of the series into a selected one of the sleeve-receiving spaces, formed by the notches 92. Aiding in accomplishing this function is a means for engaging the end sleeve and for moving it from the magazine 38 to a position opposite the correctly-sized and paired notches 92. As best shown in Figs. 1, 2 and 4, the invention employs a finger means in this connection, comprising two angular fingers 94 pivoted to a pin 95 traversing the bar 80, there being one finger 94 on each side of the bar to provide a dual support for the sleeve. The inward position of the fingers 94 is determined by engagement with a pair of projections 96 extending from opposite sides of the body portion 72 in the path of movement of the fingers. In addition, each finger is resiliently urged into this inward position by a wire spring 96a with one end bent to engage the bar 80 the spring being looped around the end of the pin 95 with its other end bent to engage the back of the finger 94.

The inner end of each finger 94 is bifurcated to partially encompass the sleeve and position this sleeve between upper and lower lips 97 and 98 provided by the bifurcated construction. In addition, the upper end of the base wall 40 of the magazine provides two downwardly extending slots 99 (Fig. 2) terminating just below the uppermost end sleeve when positioned by the tongue 50. These downwardly extending slots 99 receive the bifurcated ends of the fingers 94 when the carriage structure is in a retracted position, the lower lip 98 slipping beneath the end sleeve. Further upward movement of the carriage structure 65, under the action of the spring 86, will force the end sleeve past the releasable means formed by the tongue 50, the released sleeve being carried upward between the lips 97 and 98 to a position opposite the correctly-sized notches 92. By adjustment of the bar 80 relative to the body portion 72, the bifurcated ends of the two fingers 94 will lie opposite any one of the pairs of notches 92. In Fig. 1, the device is shown adjusted for sleeves of maximum size, the fingers being positioned opposite

the lowermost and largest pair of notches 92. To accommodate sleeves of smaller size the thumb screw 85 is unscrewed and the bar 80 readjusted until the fingers 94 lie opposite that pair of notches 92 forming the correct-sized sleeve-receiving space.

From the above it will be clear that the carriage structure 65 is moved from an advanced position to or through a retracted position and again to the advanced position to release the uppermost sleeve and move it to the operating station 31. The retracted position will be sufficiently displaced from the advanced position to permit the bifurcated fingers to engage the uppermost end sleeve. Further downward movement of the carriage structure 65 is not disadvantageous as the fingers 94 will merely be displaced outwardly by engagement with the lower walls of the respective slots 99 to ride along the external surface of the base wall 40 of the magazine 38. When the carriage structure again moves upwardly, under the action of the spring 86, the fingers will slide upwardly along the base wall 40 of the magazine until they come opposite the slots 99 whereupon they will enter the slots, grab the uppermost end sleeve, displace it from the magazine and carry it upwardly to the operating station while opposite or within the appropriate sized notches 92.

It is desirable that the jaw members 66 and 67 be moved toward each other during such advancing movement of the carriage structure 65 to bring the jaw members into lightly-engaging relationship with opposite sides of the sleeve being carried upward by the fingers 94. To accomplish this and also to provide for the ultimate inward compression of the sleeve when at the operating station, I provide a suitable cam means constructed as follows. Somewhat below the shaft 32 is a slightly inclined cam surface 100 formed on the operating handle 25 and intersecting a cam surface 101 of greater inclination to form a pressure member or lobe 102. As the operating handle 25 is squeezed the lobe 102 will, of course, move inwardly. Related cam surfaces are formed on the upper outer end of the bar 80. These cam surfaces include an auxiliary cam surface 104 of slight inclination, another auxiliary cam surface 105 of greater inclination and a main cam surface 106 of slight inclination.

The operation of these coating cam surfaces can best be understood from Fig. 1, remembering that the carriage structure 65 is here shown in an intermediate position assumed during its movement from a retracted position to an advanced position. As the carriage structure continues its upward movement, from the position shown in Fig. 1, the auxiliary cam surface 104 comes closer to and may engage the cam surface 100 of the handle member 25 with consequent slight movement of the jaw member 67 toward the jaw member 66. Further upward movement of the carriage structure 65 will bring the auxiliary cam surface 105 into sliding engagement with the cam surface 101 of the handle member, whereupon further upward movement will force the jaw member 67 rapidly toward the jaw member 66. This movement tends to close the sleeve-receiving space to bring the jaw members closer to the sleeve periphery. Such rapid movement of the jaw members toward each other is terminated when the lobe 102 passes the junction of the cam surfaces 105 and 106. Further upward movement of the carriage structure will cause the main cam surface 106 to slide along the cam surface 100 of the operating handle 25

to compress the jaw members lightly against the sleeve. The pressural engagement between the main cam surface 106 and the cam surface 100 will limit the upward movement of the carriage structure under the action of the spring 86 and will act as a stop to determine the advanced position of the carriage or the adjustment screw 88 can be set to serve this stopping function. At this advanced position the sleeve, lightly clamped between the jaw members, will be at the operation station.

To deform the sleeve 12 locally, e. g., to form the depressed portions 14 and 14' and also the central depressed portion 16, if not preformed, the notches 92 of at least one jaw member are equipped with deforming projections. As shown, the jaw member 67 is longitudinally drilled at its mid plane to provide a bore 110 which intersects the bottom of each notch 92 therein. In this bore is disposed a hardened pin 111 so that each notch 92 is bounded in part by the arcuate surface of the notch and by the exposed arcuate surface of the hardened pin 111. When the jaw members are pressed together, the hardened pin 111 thus exerts a localized pressure capable of forming the depressed portion 14 or 14'. The jaw members can be urged together with considerable pressure by squeezing the handle 25, the lobe 102 pressurally engaging the main cam surface 106 at this time.

In the illustrated embodiment, the hardened pin 111 is centered with respect to the magazine 38 and the sleeves 12 therein. Correspondingly, if the sleeve at the operating station 31 is not axially displaced, the first squeeze of the handle 25 can form the central depressed portion 16 in an otherwise-straight sleeve. If the sleeves 12 are loaded in the magazine 38 after the central depressed portion 16 is formed, this initial squeezing operation is omitted.

While the sleeve 12 is at the operating station and held lightly by the jaw members, the end of the wire-like member 13 may be inserted in the trough 30 of the positioning member 29 and moved axially into the sleeve to engage the central depressed portion 16. The wire-like member is then moved additionally to slide the sleeve 12 axially along its sleeve-receiving space until the forward end of the sleeve engages the opposite positioning member 29' which will serve as a stop for the sleeve movement. The hardened pin 111 will now be disposed opposite an end portion of the wire-like member 13. Squeezing the handle 25 at this time will deform the sleeve to produce the depressed portion 14, thus securing the sleeve to the wire-like member 13. The pressure on the handle 25 is then released but the sleeve will remain within the sleeve-receiving space, lightly contacted by the jaw members.

The end of the second wire-like member 13' is then disposed in the trough 30 of the positioning member 29' and moved into the sleeve to engage the central depressed portion 16 thereof. Further movement of the wire-like member 13' will shift the sleeve through its original central position and move the sleeve axially until its far end engages the positioning member 29 on the opposite side of the tool. At this time the hardened pin 111 will be opposite an end portion of the wire-like member 13' and squeezing of the handle 25 will form the depressed portion 14', thus locking the sleeve to this wire-like member.

The handle 25 is now released and the cocking handle 78 is depressed until the lobe 102 clears the main cam surface 106. At this time the jaw

members separate a sufficient distance to permit the sleeve 12 with its connected wire-like members to move upwardly in the channels 28 from the tool.

When it is desired to expel another sleeve from the magazine 38 and dispose it between the jaw members, the cocking handle 78 is moved downwardly and released to withdraw the next sleeve from the magazine and move it upwardly to the operating station for sequential clamping of two additional wire-like members 13 and 13'.

One feature of the invention is that it can be set to deform sleeves of various size. When properly set the sleeve will be automatically moved to the correspondingly-sized notch 92. 15 Another important feature of the invention is that the tool can be actuated a plurality of times to perform successive deforming operations on the same sleeve.

It will be understood that a particular embodiment of the invention has been illustrated for purposes of explanation, but it should be apparent that various changes and modifications can be made without departing from the spirit of the invention as defined in the appended claims.

I claim as my invention:

1. In a compression tool for deforming a sleeve into engagement with a member positionable therein, the combination of: a body and means for storing a series of sleeves in side-by-side position therein; a carriage structure mounted on and reciprocable relative to said body and including a pair of relatively movable jaw members providing opposed notches facing each other to define a sleeve-receiving space; means on said carriage structure for moving the end sleeve of said series into said sleeve-receiving space; and means for moving said jaw members toward each other to deform said sleeve while within said sleeve-receiving space to engage said sleeve with a member placed inside said sleeve.

2. In a compression tool for deforming a sleeve into engagement with a member positionable therein, the combination of: a body and means for storing a series of sleeves in side-by-side position therein; a carriage structure mounted on and reciprocable relative to said body and including a pair of relatively movable jaw members providing opposed notches facing each other to define a sleeve-receiving space; means on said carriage structure for moving the end sleeve of said series into said sleeve-receiving space; means carried by said tool for moving the remaining sleeves of said series until a succeeding sleeve replaces said end sleeve of the series upon movement of such end sleeve into said sleeve-receiving space; and means for moving said jaw members toward each other to deform said sleeve while within said sleeve-receiving space to engage said sleeve with a member placed inside said sleeve.

3. In a compression tool for deforming a sleeve into engagement with a member positionable therein, the combination of: a body and means for storing a series of sleeves in side-by-side position therein, said body providing an operating station beyond the end sleeve of the series; displaceable means carried by said tool for retaining said end sleeve in position; a movable carriage structure mounted on said body and having means thereon for moving said end sleeve past said displaceable means to said operating station; means carried by said tool for advancing the next sleeve of the series to said displaceable means to form the end sleeve of the series; and means on

said carriage structure for inwardly deforming the sleeve at the operating station.

4. In a compression tool for deforming a sleeve into engagement with a member positionable therein, the combination of: a body providing an operating station; a carriage structure mounted on and slidably relative to said body in a direction toward and away from said operating station, said carriage structure including a jaw means; means carried by said tool for feeding a sleeve to said jaw means when at a position removed from said operating station to be transported to said operating station by said carriage structure; and means carried by said tool for compressing said jaw means against said sleeve when at said operating station to deform said sleeve inwardly.

5. In a compression tool for deforming a sleeve into engagement with a member positionable therein, the combination of: a body and means for storing a series of sleeves in side-by-side position therein, said body providing an operating station beyond the end sleeve of the series; a carriage structure mounted on and slidably relative to said body in a direction toward and away from said operating station, said carriage structure including a jaw means; means connected to said carriage structure for moving said carriage structure between retracted and advanced positions relative to said body, said jaw means being adjacent said end sleeve of said series when said carriage structure is in retracted position and adjacent said operating station when in advanced position; means carried by said tool for feeding said end sleeve of said series to said jaw means when said carriage structure is near its retracted position, said jaw means transporting this sleeve to said operating station; and means carried by said tool for actuating said jaw means so as to deform this sleeve inwardly while at said operating station.

6. A combination as defined in claim 5, in which said means for feeding said end sleeve to said jaw means includes a finger means pivoted to said jaw means for engaging said end sleeve.

7. A combination as defined in claim 5, in which said series of sleeves includes another end sleeve at the opposite end of said series from said first-named end sleeve, and including a spring means carried by said tool and engaging said other end sleeve for resiliently urging all of the sleeves of said series in a direction toward said operating station.

8. A combination as defined in claim 5, in which said jaw means includes a first jaw member, a second jaw member, and means for hinging said second jaw member relative to said first jaw member to move toward and away from said first jaw member, said jaw members providing a plurality of opposed sleeve-receiving notches facing each other to provide a plurality of sleeve-receiving spaces disposed different distances from said end sleeve of said series, and in which said feeding means includes means for feeding said end sleeve to a selected one of said plurality of sleeve-receiving spaces.

9. A combination as defined in claim 5, in which said jaw means includes a first jaw member, a second jaw member, and means for hinging said second jaw member relative to said first jaw member to move toward and away from said first jaw member, said jaw members providing a plurality of opposed sleeve-receiving notches facing each other to provide a plurality of sleeve-receiving spaces disposed different dis-

tances from said end sleeve of said series, and in which said feeding means includes a finger means pivoted relative to one of said jaw members, and means for adjusting the point of pivoting of said finger means relative to said one of said jaw members to feed said end sleeve to a selected one of said sleeve-receiving spaces.

10. A combination as defined in claim 5, in which said means for actuating said jaw means so as to deform said sleeve inwardly while at said operating station includes a handle pivoted to said body, and a pressure member operatively associated with said handle to engage said jaw means to compress same against said sleeve.

11. A combination as defined in claim 5, in which said means for actuating said jaw means so as to deform said sleeve while at said operating station includes a handle pivoted to said body, a first cam surface carried by said handle, and a second cam surface carried by said jaw means to engage said first cam surface when said carriage structure is in said advanced position.

12. A combination as defined in claim 5, in which said means for actuating said jaw means so as to deform said sleeve while at said operating station includes a handle pivoted to said body, a first cam surface carried by said handle, and an auxiliary cam surface carried by said jaw means and engageable with said first cam surface during movement of said carriage structure from its retracted position to its advanced position to engage said jaw means with said end sleeve before said advanced position is reached.

13. In a device for inwardly deforming in sequence a plurality of sleeves removably retained side-by-side in a magazine, the combination of: a body providing a magazine-receiving space and means for retaining said magazine in said space, said body providing an operating station beyond the end of said magazine; first and second jaw members mounted on and movable relative to said body in unison and providing opposed notches facing each other; means for mounting one of said jaw members to move toward the other; means carried by one of said jaw members for moving a sleeve from said magazine to a position between said jaw members; and means carried by said device for moving said one of said jaw members toward the other jaw member to deform said sleeve inwardly.

14. In a device for inwardly deforming in sequence a plurality of sleeves removably retained side-by-side in a magazine, the combination of: a body providing a magazine-receiving space and means for retaining said magazine in said space, said body providing an operating station beyond the end of said magazine; first and second jaw members providing opposed notches facing each other to define a sleeve-receiving space; means for mounting said jaw members to move longitudinally of said magazine and toward and away from each other to translate said sleeve-receiving space from a position near said magazine to said operating station and to decrease and increase the size of said sleeve-receiving space; means for moving a sleeve from said magazine into said sleeve-receiving space when this space is near said magazine; means for moving this sleeve while in said sleeve-receiving space to said operating station; and means for moving one of said jaw members toward the other while said sleeve is at said operating station to deform said sleeve inwardly.

15. In a device for inwardly deforming in se-

quence a plurality of sleeves removably retained side-by-side in a magazine, said magazine including releasable means for retaining said sleeves therein, the combination of: a body providing a magazine-receiving space and means for retaining said magazine in said space, said body providing an operating station beyond the end of said magazine; spring means carried by said body and engaging the lowermost of said sleeves to resiliently urge said sleeves upwardly and to resiliently urge the uppermost sleeve against said releasable means; a carriage structure slidably longitudinally of said magazine and comprising a jaw means including first and second jaw members providing opposed notches facing each other to define a sleeve-receiving space, said carriage structure being movable from a retracted position at which said sleeve-receiving space is near said magazine to an advanced position at which said sleeve-receiving space is adjacent said operating station; finger means carried by said jaw means to engage the upper end sleeve when said carriage structure is in said retracted position and to advance same beyond said releasable means of said magazine and into said sleeve-receiving space during movement toward said advanced position to carry said upper end sleeve to said operating station; and means for moving said jaw members together to deform inwardly said sleeve while at said operating station.

16. In a tool of the character described for deforming an article, the combination of: a body providing an operating station and having means for storing articles to be deformed at a location spaced from said operating station; jaw means movable relative to said body toward and away from said operating station for deforming an article at said operating station, said jaw means comprising a pair of relatively movable jaw members having a plurality of pairs of opposed notches providing a plurality of article-receiving spaces; and selecting means on said jaw means for transporting an article from said storing means to said operating station and for positioning same in a selected one of said article-receiving spaces.

17. A tool as set forth in claim 16 wherein said selecting means is adjustable relative to said jaw means to permit positioning of an article removed from said storing means by said selecting means in any one of said article-receiving spaces.

18. A tool as set forth in claim 17 wherein said selecting means includes finger means adapted to be aligned with any one of said article-receiving spaces.

19. In a tool of the character described for deforming an article, the combination of: means for storing an article to be deformed; jaw means movable relative to said storing means toward and away from an operating station for deforming the article at said operating station, said jaw means being provided with a plurality of article-receiving spaces; and selecting means adjustably connected to said jaw means and adapted to register with a selected one of said article-receiving spaces for moving the article from said storing means to said operating station and for positioning same in said selected article-receiving space.

20. A tool as set forth in claim 19 including means for adjusting said selecting means relative to said jaw means so as to bring said selecting means into registry with various ones of said article-receiving spaces.

21. In a tool of the character described for deforming a sleeve onto an article such as a wire inserted into the sleeve, the combination of: a body; jaw means carried by said body and including a pair of relatively movable jaw members adapted to receive the sleeve therebetween, said jaw members being movable inwardly toward each other with the sleeve disposed therebetween to deform the sleeve inwardly onto the article inserted into the sleeve, the sleeve being movable relative to said jaw members along its own axis while disposed between the jaw members and before the jaw members are moved inwardly toward each other to deform the sleeve; means carried by said tool for moving said jaw members inwardly toward each other to deform the sleeve; and means carried by said tool for limiting movement of the sleeve relative to said jaw members along its own axis, including elements engageable with the ends of the sleeve.

22. A tool as defined in claim 21 wherein said elements are mounted on one of said jaw members.

23. A tool according to claim 21 wherein each of said elements is provided with a notch therein to receive the article inserted into the sleeve. 25
